PNEUMATICALLY OPERATED DIE-CASTING MACHINE

Leonard Arthur Catlin and Wilfred Henry Cockrell, West Bromwich, England, assignors to E. M. B. Company Limited, West Bromwich, England

Application June 22, 1940, Serial No. 341,978
In Great Britain September 1, 1939

5 Claims. (Cl. 22—92)

This invention relates to pneumatically operated die-casting machines, and has for its object to provide improved means for controlling the movements of the dies of such machines.

The invention comprises the combination with a pneumatically operable and relatively slidable piston and cylinder for actuating the movable die head of the machine, and means operable by the attendant for controlling flow of air to and from the said cylinder, of a hydraulic locking device for interrupting the movements of the said die head at desired positions, and controlling means therefor.

In the accompanying sheets of explanatory drawings—

Figure 1 is a part sectional front elevation, Figure 2 an end elevation, and Figure 3 a fragmentary plan, of a hydraulic locking device constructed in accordance with the invention and applied to a pneumatically operable and relatively movable piston and cylinder for actuating the movable die-carrying plate of a die-casting machine.

Figures 4 to 6 are respectively a front elevation, a part sectional plan, and a part sectional side elevation, of the valve mechanism and associated parts employed for controlling the flow of compressed air to and from the cylinder, these figures being drawn to a larger scale than Figures 1 to 3.

As shown in the drawings we employ, for actuating the movable head *a* which carries a die part or parts of a die-casting machine, a piston *b* which is slidable in a cylinder *c* under the action of compressed air. The piston *b* is secured on a rod *d* which at one end passes through a gland *e* in the corresponding end of the cylinder *c* and is connected by a cross head *f* and toggle linkage *g* to the die head *a*. In Figure 3 the head *a* is shown in full lines in one extreme position, and in broken lines in the other extreme position. Communicating with opposite ends of the cylinder *c* are a pair of passages *h* through which compressed air can flow between the cylinder and a pair of valve chests *i* on the underside of the cylinder. Each of these valve chests contains a spring-loaded inlet valve *j* and a spring-loaded outlet valve *k*, the valves in the one chest serving to control the flow of compressed air to and from one of the passages *h*, and the valves in the other chest serving to control the flow of compressed air to and from the other of the said passages. The valve chests *i* are situated at a sufficient distance apart to accommodate between them cams *m* for actuating the valves *j*, *k*, these cams being

mounted on a transverse shaft *n* which is rotatably supported by bearings *o* on the cylinder *c*. Mounted on the front end of the cam shaft *n* is a hand lever *p* whereby the shaft can be rocked to actuate the valves *j*, *k*, the stems of these valves being provided with abutment pieces *q*, *r*, which project through the adjacent sides of the chests *i* into the path of the cams *m*.

In applying the invention as shown to the 10 pneumatically operable apparatus above described, we form or secure on the end of the piston rod *d* remote from the cross head *f* a coaxial extension *s* which passes through a gland *l* in the adjacent end of the air cylinder *c*, and on this

15 extension we mount another piston *t*, the latter being slidable in another cylinder *u* which is arranged coaxially with and secured to the air cylinder, and which is filled with oil or other liquid at both sides of its piston.

20 At each end of its upper side the cylinder *u* is provided with an opening *v* for establishing communication between this cylinder and an oil or other liquid container *w* formed or secured on the upper side of the cylinder. The openings *v* are controlled by poppet valves *x* on the lower ends of vertical stems *y* which are slidable in fixed guides *z* situated in the container *w*. The valves *x* are loaded by springs *2* which are arranged between heads *3* on the stems and shoulders *4* on the guides *z*, and which serve to hold the valves in their closed positions for interrupting communication between the cylinder *u* and the container *w*.

25 For opening the valves *x* against the action of the springs *2*, we employ a pair of rockers *5* which are mounted, with one pair of ends adjacent to each other, on parallel shafts *6* in the upper part of the container *w*, and which are operable by the action on their adjacent ends of 30 a cam or cams *7* situated in the container at a position between the rockers, the other ends of the rockers being adapted to act on the heads *3* on the valve stems *y*.

The cam or cams *7* is or are mounted on a 35 rotatable shaft *8* which extends through the container *w*, and which at one end carries an arm *9*, the latter being connected by a link *10* to another arm *11* secured to the cam shaft *n*.

The hand lever *p* for rocking the cam shaft 40 *n* is formed or provided at its lower end with a pair of abutments *12*, *13*, arranged in different planes, and at a position adjacent to this end is pivotally connected to a slotted extension of the cam shaft by a transverse pin *14* so that the lever is capable of pivotal movement in a plane

containing the axis of the cam shaft. The lever abutments 12, 13 are adapted to co-act respectively with another pair of abutments 15, 16 for actuating the lever p in the manner hereinafter described. These latter abutments 15, 16 are adjustably mounted in spaced relationship and in different vertical planes on rods 17 which are connected at one end to the head a and are slidably supported adjacent to the other end by a bracket 18 depending from the cylinder c . Normally the lever abutments 12, 13 are situated in the paths of the corresponding abutments 15, 16, but they can be moved out of these paths by appropriate movement of the hand lever p about its pivot pin 14 in a forward direction.

In the initial position of the parts above described the head a and hand lever p occupy the positions shown in full lines in Figure 1, and the valves j , k , x , are closed. To impart a forward or die-closing movement to the head, that is movement towards the left in Figure 1, the hand lever p is moved from the idle position shown in full lines in Figure 1 to the position p^2 shown in broken lines. During this movement of the hand lever p it passes another position p^1 also shown in broken lines. The movement of the hand lever between its idle position and the position p^1 causes one of the cams m to open the appropriate valves j , k , for admitting compressed air to the cylinder c at the right hand side of the piston b , and releasing the air from this cylinder at the other side of its piston. The piston b , however, cannot be moved by the action of the compressed air until the valves x of the liquid cylinder have been opened, this being effected by the movement of the hand lever p from position p^1 to position p^2 . When the hand lever p reaches the latter position the piston b commences to move the head a towards the left, and this movement continues until the abutment 15 comes into contact with the lever abutment 12 and, by acting on the latter, returns the hand lever to the position p^1 for re-closing the valves x of the liquid cylinder u . The closing of these valves prevents the flow of liquid between the cylinder u and the container w , and thereby prevents further movement of the piston t . Consequently, the movement of the air piston b and the head a is interrupted. For enabling the piston b and head a to continue their movement towards the left, the hand lever p is pulled forwards against the action of a spring-loaded plunger 19, and then returned to the position p^2 , the forward movement of the lever causing it to move about the axis of the pivot pin 14 into a position in which the lever abutments 12, 13 are out of the paths of the movable abutments 15, 16 as shown in broken lines in Figure 2. The head a is now moved by the piston h to its closed position as indicated by broken lines in Figure 3.

When it is desired to return the head a to its initial position, the hand lever p is moved past the central position to the position p^4 shown in broken lines in Figure 1, and during this movement also passes another position p^3 . The movement of the hand lever between the central position and the position p^3 causes one of the cams to open the appropriate valves j , k , for admitting compressed air to the cylinder c at the left hand side of the piston b , and releasing the air from this cylinder at the other side of its piston. The piston b , however, cannot be moved by the action of the compressed air until the valves x of the liquid cylinder have been opened, this being effected by the movement of the hand lever p

from the position p^3 to the position p^4 . During the return movement of the head a the abutment 16 co-acts with the lever abutment 13 to return the lever p to the position p^3 for interrupting the movement of the head a , the lever being subsequently pulled forwards as above described, and returned to position p^4 for enabling the return movement of the head to be continued under the action of the compressed air on the piston b .

By suitably adjusting the positions of the abutments 15, 16 on the rods 17 the movements of the head a can be interrupted at any desired positions, and by providing additional abutments on the rods each movement of the head can be interrupted at more than one predetermined position if desired.

From the foregoing it will be seen that the liquid cylinder, piston and associated parts form a simple and convenient hydraulic locking device which serves automatically to interrupt the movements of the head a which carries a die part or parts in a reliable manner and exactly at predetermined positions, this arresting of the head being required to enable cores to be inserted and withdrawn from between the fixed and movable die parts of the casting machine when the die parts are in appropriate relative positions. It will also be seen that the hand lever p can be operated by the attendant for causing the locking device to interrupt the movement of and lock the head a in any desired position.

When the apparatus above described is used in a die casting machine in which molten aluminium or other metal is injected between the die parts under the action of compressed air, it is desirable not only to prevent the molten metal from being injected excepting when the die parts are closed, but also to prevent the die parts from being opened while the molten metal is under air pressure. To satisfy these conditions we employ a rotatable shaft 20 for actuating valve mechanism (not shown) adapted to control the supply of compressed air to metal injecting means (also not shown). This shaft is supported in fixed bearings 21 at the end of the air cylinder c adjacent to the die head a , and is provided at its front end with an operating handle 22, the other end of the shaft being connected in any convenient manner to the valve mechanism above mentioned. Also the shaft 20 is formed at different positions with a pair of flattened parts 23, 24 which are situated respectively in key-hole or like slots 25, 26 formed in members 27, 28. The member 27 is formed or provided on one end of a rod 29 which at its other end is pivoted to the arm 11 on the cam shaft n , and the member 28 is formed or provided on one end of a rod 30 which at its other end is slidably supported by a fixed part 31. Both of the slots 25, 26 are formed as shown with narrow portions which (when occupied by the corresponding flattened portions 23, 24 of the shaft 20) serve to prevent rotational movement of the shaft, and with enlarged portions which communicate with one end of the narrow portions, the enlarged portions of the slots being such that (when occupied by the flattened portions of the shaft) they permit rotational movement of the shaft.

When the apparatus is in its initial or inoperative position as shown the flattened portions 23, 24 of the shaft 20 occupy the narrow portions of the slots 25, 26 and rotational movement of the shaft 20 for actuating the compressed air valve mechanism of the metal injecting means is prevented. If now the hand lever p is moved to the

position p^2 , the rod 29 is moved into a position in which the flattened portion 23 of the shaft 20 occupies the enlarged portion of the slot 25 in the member 27, but rotational movement of the shaft is prevented by the engagement of its other flattened portion 24 with the narrow portion of the slot 26 in the member 28. When, however, the die plate a approaches its closed position a projection 32 on the cross head f comes into contact with an adjustable abutment 33 on the rod 30 and moves the latter against the action of a spring 34 into a position in which the flattened portion 24 of the shaft 20 occupies the enlarged portion of the slot 26 in the member 28. The shaft 20 can now receive rotational movement for actuating the valve mechanism of the metal injecting means. This rotational movement of the shaft 20 causes its flattened portion 23 to assume such a position in the member 27 that the lever p cannot be operated for effecting opening movement of the die head a until the shaft 20 has been returned to its initial position.

The invention is not limited to the example above described as subordinate details may be varied to suit requirements.

Having thus described our invention what we claim as new and desire to secure by Letters Patent is:

1. Controlling means for a die-casting machine, comprising the combination with a pneumatically operable and relatively slideable piston and cylinder for actuating the movable die head of the machine, and means operable by the attendant for controlling flow of air to and from the said cylinder, of a hydraulic locking device for interrupting the movement of and locking the die head in any desired position under the control of the attendant, and means responsive to the movement of the die head whereby the said device is brought into action automatically for locking the die head in at least one predetermined position.

2. Controlling means for a die-casting machine, comprising the combination with a pneumatically operable and relatively slideable piston and cylinder for actuating the movable die head of the machine, and valves for controlling the flow of air to and from the ends of the cylinder, of a second piston and cylinder, the two pistons being interconnected, valves for controlling the flow of liquid to and from the ends of the second cylinder, a lever operable by the attendant for controlling both sets of valves, a pair of abutments on the valve-controlling lever, and additional abutments movable with the die head and adapted by co-acting with the lever abutments, after the lever has been actuated to open the liquid valves, to effect the closing of the liquid valves, the lever being movable in one plane for

controlling the air and liquid valves, and in another plane at right angles to the first plane for moving the lever abutments out of the path of the other abutments.

5 3. Controlling means for a die-casting machine, comprising the combination with a pneumatically operable and relatively slideable piston and cylinder for actuating the movable die head of the machine, and means operable by the attendant for controlling flow of air to and from the cylinder, of a second relatively slideable piston and cylinder respectively connected to the pneumatically operable piston and cylinder, a liquid container situated above the second cylinder, a pair of spring-loaded poppet valves for controlling communication between the liquid container and the ends of the second cylinder, rockers for actuating the valves, a lever operable by the attendant, at least one cam for actuating the rockers, linkage connecting the cam to the lever, and means movable with the die head for actuating the said lever.

4. Controlling means for a die-casting machine, comprising the combination with a pneumatically operable and relatively slideable piston and cylinder for actuating the movable die head of the machine, and valves for controlling the flow of air to and from the ends of the cylinder, of a second piston and cylinder, the two pistons being interconnected, valves for controlling the flow of liquid to and from the ends of the second cylinder, a lever operable by the attendant for controlling both sets of valves, a rotatable shaft on which the controlling lever is mounted, cams on the shaft for actuating the air valves, linkage connected to the shaft for actuating the liquid valves, and means movable with the die head for actuating the said lever.

50 40 5. Controlling means for a die-casting machine, comprising the combination with a pneumatically operable and relatively slideable piston and cylinder for actuating the movable die head of the machine, and valves for controlling the flow of air to and from the ends of the cylinder, of a second piston and cylinder, the two pistons being interconnected, a liquid container situated above the second cylinder, spring-loaded poppet valves for controlling communication between the liquid container and the ends of the second cylinder, rockers for actuating the liquid valves, a lever for controlling both sets of valves, at least one cam for actuating the rockers, linkage connecting the cam to the controlling lever, a rotatable shaft on which the controlling lever is mounted, cams on the shaft for actuating the air valves, and means movable with the die head for actuating the said lever.

LEONARD ARTHUR CATLIN.
